UNITED STATES PATENT OFFICE.

HENRY JOHN HEDLER, OF OCCUM, CONNECTICUT.

THREAD-CUTTING ATTACHMENT FOR LOOM TEMPLES.

Application filed November 9, 1922. Serial No. 599,843.

To all whom it may concern:

Be it known that I, HENRY J. HEDLER, a citizen of the United States, residing at Occum, in the county of New London and State of Connecticut, have invented certain new and useful Improvements in Thread-Cutting Attachments for Loom Temples; and I do declare the following to be a full, clear, and exact description of the invention, such as will enable others skilled in the art to which it appertains to make and use the same.

This invention relates to an attachment to be used in connection with a loom temple and to serve as means for cutting thread extending from the woven cloth at the selvage.

One object of the invention is to provide an attachment which can be put in place in connection with a loom temple having substantially a conventional construction, it being only necessary to make a slight change in construction in order to permit of the thread cutting attachment being put in place.

Another object of the invention is to so construct this attachment that when in use, it will have no tendency to cut the selvage edge of the cloth, but at the same time serve to very effectively cut the protruding end portions of the old and the new threads.

Another object of the invention is to so construct this cutting attachment that when in use, the threads will not have a tendency to wind upon the cutting attachment and thus serve to prevent proper operation of the same.

Another object of the invention is to provide an attachment which can be very easily put in place and may be firmly held in the proper position when in use.

Another object of the invention is to so construct this attachment that the cutting blades may be firmly held in place by frictional grip and may permit of removal for sharpening purposes without it being necessary to take the temple apart or remove the attachment from the temple.

Another object of the invention is to so construct the attachment that it is not necessary to exert pressure which would tend to interfere with proper rotation of the temple roll. It has been found that when pressure is exerted, the temple roll will cause the fabric to be marked by the teeth of the roll and the fabric thus damaged. This

objection has been found to exist in connection with thread cutters including a stationary blade and a rotary blade, the cutters of the type mentioned being further open to the objection that the threads have a tendency to wind about the stem portion of the rotary blade and prevent operation thereof. In view of the objections noted in connection with the cutters which include a stationary blade and a rotary blade, these have not been found satisfactory and therefore at the present time it is customary to leave the threads upon the cloth and then remove them by singeing. This singeing is objectionable since it often happens that the threads will be burnt too close and the selvage edge will be damaged.

This invention is illustrated in the accompanying drawing, wherein:

Figure 1 is a view showing a loom temple in side elevation and provided with the improved cutting attachment.

Figure 2 is a sectional view taken along the line 2—2 of Fig. 1.

Figure 3 is a view showing the loom temple in end elevation.

Figure 4 is a transverse sectional view taken along the line 4—4 of Fig. 3.

Figure 5 is a transverse sectional view taken along the line 5—5 of Fig. 2.

Figure 6 is a group view showing in perspective one of the temple rolls and the cutting attachment to be associated therewith.

This temple is of substantially a conventional construction and includes a box B having a slide bar S which extends into the usual slide bar box S'. The box is further provided with the usual stop arm A which will be hit by the lay of the loom in order to move the slide bar against the action of the usual spring provided in the slide bar box. The box B is provided with the usual pod 1 and cap 2 which is provided at one end with the usual head 3 through which extends the usual fastener bolt 4 which serves to releasably secure the cap in place. The usual temple rolls 5 and 6 are positioned within the box and rotatably mounted upon the usual spindles which extend longitudinally of the pod 1 and are designated by the numerals 5' and 6'. So far the temple described is of a conventional construction and no claim is made to the same.

The cutting attachment will be associated

with the temple roll 5 and comprises the elements shown in perspective in Fig. 6. This cutting device is provided with a blade 7 which is formed of razor steel and is substantially rectangular in shape and has its lower end provided with a sharpened edge 8 against which the threads are to be cut. This blade is carried by a holder 9 which may be termed a blade carrying frame and is provided with side flanges 10 and 11 for engaging opposite edges of the blade. It should be noted that the flanges 10 and 11 are undercut from their inner faces so that they overhang the outer face of the blade 13 and thus prevent the blade from moving out of proper position when placed in the carrier frame 9. At its upper end, this carrier frame 9 is provided with a side arm 12 having a fastener receiving opening 13 and at its lower end the frame has been provided with an enlarged lower end portion 14 provided with a diagonally disposed slot 15 and an opening 16. This opening 16 is of sufficient size to permit the hollow side arm 17 or sleeve 17 of the toothed wheel 18 to pass through the opening 16 and permit easy rotation when this sleeve 17 is passed through the opening 16 and tightly fitted into the end of the roll 5. It will thus be seen that the attachment will be connected with the roll 5 and when in place, the roll 5 and wheel 18 may rotate upon the stem 5' and the sleeve 17 turn in the opening 16 without binding.

In order to put the cutting attachment in place, the pod 1 has been provided with a groove 19 to receive the lower end portion of the frame 9 and the head portion 20 of this pod has been provided with a recess 21 which receives the thread engaging wheel 18. The head 3 of the cap 2 has its end face provided with a recess 22 to receive the side arm 12 and a threaded socket leads from this recess to receive the fastener screw 23 which passes through the side arm to hold the frame in the vertical position. At the junction of the cap 2 and head 3 there has been provided a slot 24 which is positioned above the slot 19 so that the frame 9 may extend into this slot 24 when in the position shown in Figs. 1, 3 and 4. It will thus be seen that the attachment can be put in place and when in place will be firmly seated and will be firmly held in place and will not be in the way.

When the attachment is in place and the loom in operation, the fabric passes through the box B beneath the cap 2 and passes over the rollers 5 and 6. During operation, the lay of the loom strikes the stop arm A and moves the slide bar S longitudinally of the slide bar box S'. Therefore, the slide bar is caused to have reciprocating movement and as it moves the rollers 5 and 6 are caused to roll along the woven fabric and of course

rotate. The rollers do not make a complete revolution but simply rotate each for a part of a revolution and therefore the rollers do not have a complete rotary movement but instead have an oscillating movement. The fabric as it is woven of course moves slowly and therefore threads which protrude beyond the selvage edge gradually move into position for engagement by the teeth of the thread engaging wheel 18. The teeth of this wheel 18 will engage the threads and as the wheel oscillates with the roller 5, these protruding threads will be brought into engagement with the cutting edge 8 of the blade 7 and move back and forth along this edge until they are cut off. When it is desired to sharpen the cutting blade, the upper end portion can be grasped by means of a pair of pliers and the blade easily drawn out of the carrying frame 9. After it has been sharpened, it can then be easily put back in place. It will thus be seen that there has been provided a device which will be very efficient in operation and can be easily applied to a loom temple of a conventional construction.

While the cutter has been shown used in connection with a temple of the double roll type it is to be understood that it may also be applied to a temple of the single roll type in which the cloth passes under the roller instead of over the roller.

I claim:

1. The combination with a loom temple including a box and a temple roller, of thread engaging means actuated by said roller, a blade carrying frame, loosely connected at its lower end to said thread engaging means and its upper end removably secured to said box, and a cutting blade mounted on and co-acting with said carrying frame to cut the threads.

2. The combination with a loom temple including a box and a temple roller in said box of thread cutting means including a thread engaging wheel carried by and turning with said roller, a blade carrying frame, positioned vertically and having its lower end removably secured to said thread engaging wheel and its upper end removably secured to said box and a blade secured to said blade carrying frame.

3. The combination with a loom temple including a box and a temple roller, of thread cutting means including a thread engaging wheel carried by and turning with said roller, a blade carrying frame removably connected at its upper end to said box and having its lower end loosely connected with said thread engaging wheel and provided with a thread receiving slot, and a cutting blade secured to said carrying frame in operative relation to said slot.

4. The combination with a loom temple including a box and a temple roller in said

box, of thread cutting means including a thread engaging wheel turning with said roller, a blade carrying frame having blade gripping flanges and removably connected 5 with said box and having a thread receiving slot, a cutting blade mounted on and gripped by the flanges of said carrying frame, and having its cutting end positioned in operative relation to the slot in said carrier.

10

5. The combination with a loom temple including a box and a temple roller in said box, of thread cutting means including a thread engaging wheel having a hub exten-

sion engaged with said roller for turning 15 therewith; a blade carrying frame provided with a slot and having its upper end removably secured to said box and its lower portion loose on the hub extension of said thread engaging wheel, a cutting blade positioned vertically on and secured to said carrier frame said blade having its lower end sharpened and positioned in operative relation to the slot in said carrier frame.

20

In testimony whereof I have hereunto af- 25 fixed my signature.

HENRY JOHN HEDLER.
